DESIGN FOR A TWISTED PLASTIC TUBE

Karl Schick, New York, N. Y.

Application September 11, 1945, Serial No. 122,003

Term of patent 7 years

(Cl. D87—3)

To all whom it may concern:

Be it known that I, Karl Schick, a citizen of Czechoslovakia, residing in New York, in the county of New York and State of New York, have invented a new, original, and ornamental Design for a Twisted Plastic Tube, of which the following is a specification, reference being had to the accompanying drawing, forming a part thereof, wherein:

Fig. 1 is a perspective view of the tube showing my new design;

Fig. 2 is an enlarged end perspective view of a portion of the tube shown in Fig. 1.

The characterizing feature of my design resides in a twisted transparent tube of the configuration shown, ornamented on the interior thereof with spirally convoluted design of interlaced circles, as shown.

I claim:

The ornamental design for a twisted plastic tube, substantially as shown and described.

KARL SCHICK.
